HENRY E. HULL AND BURLIN T. MERRITT, OF SAG HARBOR, NEW YORK.

Letters Patent No. 85,097, dated December 22, 1868.

IMPROVEMENT IN WINDOW-FRAMES.

The Schedule referred to in these Letters Patent and making part of the same.

To all whom it may concern:

Be it known that we, HENRY E. HULL, and BURLIN T. MERRITT, of Sag Harbor, in the county of Suffolk, and State of New York, have invented a new and improved Stop-Fastener for Windows; and we do hereby declare that the following is a full, clear, and exact description thereof, which will enable those skilled in the art to make and use the same, reference being had to the accompanying drawings, forming part of this specification.

This invention relates to an improvement in the method of fastening the stop or bead-casings which hold in the sashes of windows; and

It consists in the application of an eccentric-lever for that purpose, in combination with a pin in the bead or stop-casing, and in the manner hereinafter more fully described.

Figure 1 represents a sectional front inside elevation of the window with the eccentric applied, as when fastening the stop-casing.

Figure 2 is a detailed view of the fastening-device on an enlarged scale, in order to show to better advantage its construction and operation.

Similar letters of reference indicate corresponding parts.

A A represent the upper and lower sashes of the window;

B is the face-casing of the window; and

C represents the stop or bead-casings by which the sashes are held in their places.

D is the eccentric-lever, which may be attached to and have its pivot or fulcrum in a metallic frame, E, as seen in fig. 2, and the frame mortised into the jamb of the window, as seen at F, in fig. 1, or it may be connected directly with the jamb-casing or window-frame by a simple pivot, as seen at G, fig. 1.

In either case a mortise is made in the jamb to receive the eccentric-lever, and sufficiently long vertically to allow the eccentric the necessary play or movement up and down.

A mortise or slot is made entirely through the bead-casing C, which is seen in the drawing, fig. 1, at g.

Securely fixed in this mortise or slot there is a pin, i.

The pivot or fulcrum of the eccentric-lever is marked k. Upon this point k the eccentric-lever turns.

The inner portion of the eccentric-lever forms a curved line, drawn from its extreme point m, which line approaches the central pivot k, and terminates at a point near the central pivot, so that when the eccentric is drawn down over the pin i, the tendency is to draw the pin and the bead-casing towards the central pivot k, and consequently to press the bead-

casing against the jamb of the window, with any force which may be required to keep it in place.

The slot g, through the bead or stop-casing, may be broad enough to allow the bead to be moved or crowded against the sash, to keep the sash tight, or to prevent its rattling.

To remove the bead-casing from the window, for taking out the sashes, it is only necessary to raise the eccentric by the projecting end n, which turns it back into the mortise, thereby releasing the pin i, and the casing or bead, which is then readily removed.

This is but a moment's work, and the arrangement avoids the necessity of using nails or screws, and thus injuring and defacing the bead.

One or more of the eccentrics may be used to a bead, as may be deemed necessary, either with or without the frame E.

The form of the eccentric may be somewhat varied, and the same or a similar result be produced.

We do not therefore confine ourselves to the particular form of the eccentric taken as a whole, but propose to use any form of lever, whereby an increasing pressure on the bead-casing is produced by an eccentric movement.

Neither do we limit ourselves to the particular arrangement shown in the drawing.

The eccentric might be attached to the bead-casing and the pin i placed in the jamb, but we prefer the method shown and described.

The advantages of this method of fastening are many and obvious, and must be appreciated by all who have been annoyed with rattling windows, or have been troubled in taking off the stop-casing for removing the sashes, for washing, glazing, or other purposes.

We claim as new, and desire to secure by Letters Patent—

1. The eccentric-levers D, pivoted within the case E, or within the window-jamb at G, and adapted to fit over the pin i in the slot g of the stop or bead, all operating as described, whereby the depression of the lever draws the bead firmly within the casing, as herein shown and described, for the purpose specified.

2. The combination of the eccentric-lever D and pin i with the window-casing and the slotted bead C, whereby an increasing pressure is produced by the eccentric movement of the lever, substantially as described, for the purpose specified.

HENRY E. HULL.
BURLIN T. MERRITT.
